DENTAL INSTRUMENT

Filed March 31, 1925

Inventor.
Robert Morse Withycombe,

By *James L. Morris* Attorney

UNITED STATES PATENT OFFICE.

ROBERT MORSE WITHYCOMBE, OF SYDNEY, NEW SOUTH WALES, AUSTRALIA.

DENTAL INSTRUMENT.

Application filed March 31, 1925. Serial No. 19,707.

This invention relates to dental instruments and particularly to operative tools such as curettes, broaches and the like, having a common handle into which a plurality 5 of tools may be interchangeably and selectively secured, and the invention has for its principal object the promotion of convenience and sanitation in the use of such instruments by avoiding the need of mechanical coupling devices between the tool and handle, such as screw-threads, clamps, chucks, etc. by substituting therefor a cementitious composition of matter initially associated with either the handle or tool, and which is 10 at all times actively antiseptic and of such character as to be readily and repeatedly rendered plastic and adhesive when it is desired to insert or remove the tool relatively to the handle, but normally rigid at temperatures up to and including the boiling point 15 of water, forming a rigid bond between the tool and handle, and permitting the instrument or its parts to be sterilized by boiling, without deteriorating said bond.

Another object of the invention is the provision of an improved operating tool bendable by the operator at any desired angle, and in a definite plane and so constructed 20 as automatically to determine that point in the length of the tool at which the bending shall take place.

Other objects of the invention will appear as the following description of an illustrative embodiment thereof proceeds.

In the drawings:—

Figure 1 is a longitudinal view partly in section showing a form of my invention.

Figure 2 is a similar view taken at right angles to the position shown in Figure 1.

Figure 3 is a longitudinal view of a portion of one of the dental instruments showing the working end bent at the weakened point.

Referring now in detail to the several figures, the numeral 1 represents the handle which is preferably formed with a plain cylindrical socket 2 at one end. The tool is formed with a cylindrical shank 3 adapted slidably to fit the said cylindrical socket.

The invention contemplates the making and vending of the tool, integrally provided with a coating 4 adhering to and surrounding the end portion of said shank, said coating having characteristics in common with the

Patent No. 1,598,668, granted September 7, 1926.

"Morse" metal contains, as one of its essential ingredients a compound of copper which is inherently antiseptic, oxide of copper being considered as an example of such ingredient. Among the physical characteristics of "Morse" metal which adapts it particularly for the uses of the present invention are the facility with which it may be melted 60 at relatively low temperatures, its tenacity of adherence to metallic surfaces, when melted, its normal hardness and rigidity at ordinary temperatures, up to and above the boiling point of water, and its immunity 65 from material deterioration through repeated melting. Since there may be other substances having these qualities in common with "Morse" metal, the invention is not to be considered as limited to "Morse" metal 70 for the particular cementitious material employed.

In manufacturing the tool according to my invention, the shank is dipped into molten "Morse" metal, said shank preferably 80 having been heated beforehand to approximately the same temperature as the metal. It is then withdrawn from the mass of molten metal and permitted to cool, retaining a coating 4, as shown. It is within the scope 85 of the invention to apply the "Morse" metal or its equivalent, alternatively to the interior of the socket instead of to the shank.

In using my improved dental instrument, the preferred technique is for the operator, 90 after selecting a suitable tool to hold the socketed end of the handle in a flame until it has been heated above the melting point of "Morse" metal. The tool with the coated end is then introduced into the socket, the 95 "Morse" metal becoming liquefied so as to completely fill the interstice between the shank and socket, adhering intimately to the wall of the latter, and upon cooling, uniting the tool and handle in a unitary bond. The 100 joint thus formed is actively antiseptic, and free from any crack or crevice into which contaminated matter may lodge.

When the operator desires to change the tool he reheats the handle until the "Morse" 105 metal has again liquefied, at which time the tool may readily be withdrawn from the handle. Some of the "Morse" metal may adhere to the walls of the socket, and some 110 to the shank in the act of separation, but

this does not matter, for a small quantity adhering to either part of the instrument is sufficient for practical purposes. The melting point of "Morse" metal being higher than that of boiling water, both the tool and handle, either separately or jointed may be sterilized by boiling without risk of damaging or dislodging the "Morse" metal. If ordinary care is exercised in heating the tool or handle when applying or separating the parts of the instrument, the "Morse" metal will not be burned and can withstand the heating operation repeatedly without deterioration.

15 Aside from its furnishing a truly anti-septic coupling means between the tool and handle, the invention affords a quick and convenient means for selectively changing one tool for another while a dental operation 20 is in progress and it necessitates the provision of but one handle for a number of tools from which the selection may be made.

The tool portion of the instrument is preferably provided with a knife-tempered working end 5, the shank or an intermediate portion thereof being left bendable as indicated at 6. By this means the dentist is enabled to bend the working end of the tool angularly with respect to the shank to suit various 30 situations in which the tool is to be used thereby making a single tool fulfil the function of many tools. The shank is preferably weakened in the untempered portion by diminishing its thickness, as shown at 7, in 35 Figures 2 and 3, so that the bending will always take place at the weakened point in a definite plane and at a predetermined distance from the end of the shank which engages the handle so that the working length of the 40 shank of the instrument is at all times practically uniform. The tempered part of the shank retains its rectilinear form which is of great advantage in a dental tool, affording a "sighting" means for the guidance of the 45 operator, and also transmitting to best advantage the manipulative movement of the tool.

It is possible with this feature of the invention, for the dentist to have one hand 50 occupied at the mouth of the patient, and at the same time with the other hand to bend the instrument by pressing the working end thereof against any unyielding surface such as his mixing pallet with the certainty of the 55 bend occurring in a definite point, in a defi-

nite plane, and without deforming the rectilinear disposition of the portion of the tool below the bend.

The shank may be weakened by forming concave depressions in one or both sides of 60 the shank so that the bending of the working end of the tool will always take place in the same plane.

While I have illustrated and described what I believe to be a practical embodiment 65 of my invention, it is to be understood that the invention is broad enough to include surgical instruments, generally, in its field of application and that changes may be made from time to time in the specific form and 70 relation of the several parts, as usage may require without departing from the spirit and scope of the invention as defined by the appended claims.

Having described my invention what I 75 claim as new and desire to secure by Letters Patent, is:—

1. A dental instrument comprising a separable handle and tool therefor, one of said parts being provided with a socket, and the 80 other part having a portion telescoping within said socket, and a cementitious substance of anti-septic character previously separately associated with and hardened on one of said parts and adapted when suitably 85 temperature treated to make a unitary anti-septic joint between said parts when in telescoped relation.

2. A dental instrument comprising a separable handle and tool, one of said parts being provided with a socket and the other part having a portion telescoping within said socket, and a cementitious substance of anti-septic character previously separately 90 associated with and hardened on one of said parts and adapted when suitably temperature treated to make a unitary joint between said portions when in telescoped relation, 95 said substance being normally hard and rigid at temperatures up to and including the boiling point of water but fluid at a higher range 100 of temperature.

3. A dental tool having a tempered working end, and a bendable untempered portion, the latter being mechanically weakened at a 105 definite point and in a definite plane.

In testimony whereof I have hereunto set my hand.

ROBERT MORSE WITHYCOMBE.
